Primary Examiner — Susan Bennett Hattan*Assistant Examiner* — Marie Fast Horse*(74) Attorney, Agent, or Firm* — Young & Thompson(57) **CLAIM**

The ornamental design for a fan blade, as shown and described.

DESCRIPTION

FIG. 1 is a front, top perspective view of a fan housing showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in FIG. 3 depict portions of the fan blade that form no part of the claimed design.

1 Claim, 6 Drawing Sheets(56)
